WASHING MACHINE

Filed Dec. 7, 1927

UNITED STATES PATENT OFFICE.

ERLING BUGGE, OF SEATTLE, WASHINGTON, ASSIGNOR OF ONE-HALF TO JOHN LYNG,
OF SEATTLE, WASHINGTON.

WASHING MACHINE.

Application filed December 7, 1927. Serial No. 238,328.

This invention relates to machines for washing clothes and other articles of fabric or the like.

The object of my invention is to provide a machine of this character which will be efficient and economical in operation and in which the washing and rinsing of the goods is promoted by means of circuitous currents of water generated by means of mechanism provided therefor in the machine.

More specific objects and advantages of the invention will appear in the following description.

The invention consists in the novel construction, adaptation and combination of parts hereinafter described and claimed.

In the accompanying drawing,—

Figure 1 is a view in transverse vertical section of a washing machine embodying the present invention; and Fig. 2 is a view partly in plan and partly in horizontal section of the same.

In said drawing, the reference numeral 5 represents a circular tank which is open at the top and has at the bottom a water draw-off pipe 6 controlled by a valve 7.

Provided within the tank in proximity of its bottom wall 8 is a partition 9 to afford a compartment 10 therebelow. Said partition 30 is provided in its underside with an annular channel 11 arranged concentrically of the axis of the tank, the inner and outer peripheral walls 12 and 13, respectively, of said channel are imperforate, but the horizontal 35 portions of the partitions above and surrounding said channel are foraminated, as indicated by 14, 15 and 16. Operating within said channel is a pair of water impelling members 17 and 18 formed in the similitude 40 of marine screw propellers, the same being rigidly secured to the upper ends of vertically disposed pins 19 which are journaled in the ends 20 of aligned arms 21 of a yoke which is fixedly secured to the upper end of a vertical 45 shaft 22. This shaft is rotated by means of a motor 23 through the medium of a worm 24 on the motor's armature shaft and a worm wheel 25 provided on the shaft beneath the tank. The shaft 22 which carries said yoke is 50 journaled in a bearing box 26 rigid with the tank and forms a part of a stuffing box of which 27 indicates the gland nut.

Said bearing box constitutes the hub of a non-rotatable spur gear 28 whose teeth are 55 in continuous mesh with the teeth of pinions

29 which are fixedly secured below said yoke to the pins 19 of the respective impellers 17 and 18.

The blades of said impellers are arranged somewhat helical, the helix of one blade, preferably, being right hand and the other left hand.

In operation, the clothes or other goods to be washed are placed upon the partition 9 in saponified water or suds, whereupon the motor 23 is operated to revolvably carry the impellers 17 and 18 in a planetary course, as indicated by arrow A Fig. 2, in the channel 11; and, in being thus revolved, the pinions 29 of the respective impellers coact with the spur gear 28 to cause the impellers to rotate, in directions of arrows B, with respect to the axes of their pins 19.

With impellers having right and left hand helical blades, the rotation of the same cause 75 the suds to be drawn through the clothes downwardly by one impeller and forced upwardly through the clothes by the other impeller whereby a circulation of water in a substantially vertical plane diametrically of the 80 tank is effected.

Such vertical plane, so to speak, of the water circulation is, however, rotated progressively about the axis of the impellers' path of revolution and, in consequence, subjects the entire body of clothes to a progression of intermittently occurring up-and-down currents of the washing water to thoroughly cleanse the same.

After being thus washed, the dirty suds is 90 withdrawn from the tank by opening the valve 7; and, after closing the valve, supplying the tank with a charge of clean water for rinsing the clothes; and the impellers are actuated as explained above for circulating the 95 rinsing water. The imperforate side walls 12 and 13 of the channel 11 regulate the water so that it enters and is discharged from the channel at both the top and bottom simultaneously at opposite sides respectively of the 100 channel.

The portions 15 and 16 of the partition are foraminated to permit water to pass therethrough and thus obviate neutral spaces with regard to clothes which may be located over 105 the referred to portions of the partition.

The portion 16 of the partition surrounding the channelled portion thereof is desirably located in a plane below the general plane of the top of the partition to serve as a 110

trough for the collection of lint or other material which otherwise would tend to clog the holes in other portions of the partition.

The construction and operation of the invention will, it is thought, be understood from the foregoing description of the illustrated embodiment thereof.

What I claim is,—

1. In a washing machine, the combination 10 of a circular tank, a partition therein disposed in spaced relation with the bottom of the tank, said partition being provided in its underside with an annular channel having imperforated peripheral walls and a foraminated top wall affording communication between the spaces above and below the partition, a non-rotary spur gear provided in the tank below said partition, a rotary shaft extending axially through said gear, a yoke 15 rigidly mounted upon said shaft, pins rotatably mounted in the respective arms of said yoke, a water impeller fixedly mounted upon the upper end of each of said pins and located within said channel, a spur pinion rigid with 20 each of said pins and intermeshing with the teeth of said gear, and means to drive said shaft for actuating said impellers.

2. In a washing machine, the combination 30 of a circular tank, a partition therein disposed in spaced relation with the bottom of the tank, said partition being provided in its underside with an annular channel, a non-rotary spur gear provided in the tank below said partition, a rotary shaft extending axially through said gear, a yoke rigidly 35 mounted upon said shaft, pins rotatably

mounted in the respective arms of said yoke, a water impeller fixedly mounted upon the upper end of each of said pins and located within said channel, a spur pinion rigid with 40 said pins and intermeshing with the teeth of said gear, and means to drive said shaft for actuating said impellers.

3. In a washing machine, the combination 45 of a circular tank, a partition therefor having an annular channel in its underside, the partition above the channel being foraminated for the passage of water between the tank spaces above and below the partition, a pair of rotatable helical water-impelling 50 members arranged for revoluble travel in said channel, means to impart revoluble movement to both of said members, and means for rotating the same about their respective axes.

4. In a washing machine, the combination 55 of a tank, a foraminated partition provided therein, a shaft extending into the tank below said partition, a yoke rotatable with said shaft, a pair of portable helical water-impelling 60 members carried by said yoke, means to drive said shaft to effect the revoluble movement of said members circumferentially of the tank, and means rendered operable by the revolution of said members to rotate the same 65 to impart movement of water by said members through the foraminations of the partition in the progressive travel of said members circumferentially of the tank.

Signed at Seattle, Washington, this 26th 70 day of November, 1927.

ERLING BUGGE.
